UNITED STATES PATENT OFFICE.

WILLIAM D. McCULLOUGH AND THOMAS MAHONEY, OF DETROIT, MICHIGAN, ASSIGNEES
TO PREMIER CUSHION SPRING COMPANY, OF DETROIT, MICHIGAN, A CORPORATION
OF MICHIGAN.

UPHOLSTERY SPRING CONSTRUCTION.

1,298,747.

Specification of Letters Patent.

Patented Apr. 1, 1919.

Application filed December 27, 1918. Serial No. 268,529.

To all whom it may concern:

Be it known that we, WILLIAM D. McCULLOUGH and THOMAS MAHONEY, citizens of the United States of America, residing 5 at Detroit, in the county of Wayne and State of Michigan, have invented certain new and useful Improvements in Upholstery Spring Construction, of which the following is a specification, reference being had therein to 10 the accompanying drawings.

This invention relates to spring upholstery construction and to spring supporting strips whereby great rigidity is obtained with lightness, there being a minimum number 15 of clips or attaching parts while the assembly is made readily as there is no need of special attaching implements.

The invention consists in the matters hereinafter set forth and more particularly 20 pointed out in the appended claims.

In the drawings,

Figure 1 is a plan view partially broken away of a spring construction that embodies features of the invention, and

25 Fig. 2 is a view in detail in perspective, greatly enlarged, of a base strip and spring.

As herein shown in preferred form the main frame having the form and contour desired and usually constructed with a rim 30 wire 1, has cross strips 2 that are U-shaped in section, and are preferably bent out of sheet metal. These strips are disposed in upright position, that is, with the plane of the flanges 3 and 4 extending outwardly 35 from the base of the structure. In the case of a seat cushion the flanges are substantially upright. At intervals the strip is offset in the plane of the flanges so as to provide portions 5 at regular intervals into

40 which the base coils 6 of the usual upright coiled spring common in such constructions may be placed, the coil resting on the flange 4 for example. The edges of the flanges are pinched together as indicated at 7, and hold 45 the spring firmly in place. The shape of the offset is immaterial provided it is of a character which permits the insertion of the base coil between the flanges. Likewise the connection of the U-strip with the frame 50 itself is not *per se* a part of the invention.

As herein indicated the connection is made through the base coil of the spring but other modes of attachment of the strip to the frame directly may be employed.

Obviously, changes in the details of construction may be made without departing from the spirit of our invention and we do not care to limit ourselves to any particular form or arrangement of parts.

What we claim is:—

1. In a spring upholstery construction, a U-section strip offset in the plane of the flange portions, and a spiral spring resting on a flange edge and lying between the offset portions of both flanges which are inbent 60 to retain it.

2. In a spring upholstery construction, a U-section strip offset in the plane of the flanges, and disposed with the flange margins uppermost, and a spiral spring having 70 the base coil resting on a flange edge and lying between offset portions of both flanges which are inbent to retain it.

3. In a spring upholstery construction, a U-section strip offset in the general plane of 75 the flanges and a spiral spring with axis substantially parallel to the plane of the flanges, resting on one of the flanges and lying between the offset portions of the flanges which are inbent to retain it. 80

4. In a spring upholstery construction, a base, a U-section strip thereon offset in the plane of the flanges which extend toward the face of the construction and a spiral spring with the axis generally parallel to 85 the plane of the flanges and the base coil resting on one flange margin and lying between offset portions of both flanges which are bent to retain it.

5. In a spring upholstery construction, a 90 base, U-section strips thereon in parallel relation, each offset in the general plane of the flanges which extend toward the face of the construction and spiral springs each with a supporting coil resting on adjacent flanges 95 of a pair of strips and lying between offset portions of both flanges of each strip which are bent to retain the coil.

In testimony whereof we affix our signatures in presence of two witnesses.

WILLIAM D. McCULLOUGH.
THOMAS MAHONEY.
